TUNNEL LINER

Julius Kahn, Youngstown, and Herbert E. White,
Cleveland, Ohio, assignors to Truscon Steel
Company, Youngstown, Ohio, a corporation of
Michigan

Application March 3, 1932, Serial No. 596,628

6 Claims. (Cl. 61—45)

In that type of tunnel liner made up of sections or plates, and in which the plates are usually of metal plate having side flanges, the sections of the plates being secured together by fasteners 5 passing through the flanges, it has been the custom to have these plates or sections generally rectangular in shape, the plates when in position being thus located in circumferential rows with plates in each row in alinement. As a consequence the circumferential flanges are also in alinement.

It is an object of the invention to provide a structure which as a whole when assembled constitutes a series of endless trusses extending 15 around a circle, the flanges constituting the main members while the bodies of the plates constitute web members connecting the main members so that stresses due to pressure of the earth outside the structure are thoroughly distributed 20 throughout. This is particularly advantageous in the case of localized stresses due to boulders or soft spots in the earth.

Several embodiments of the invention are disclosed in the accompanying drawings, wherein:—
25 Figure 1 is a side elevation of a portion of a tunnel lining, in which the novel structure is employed.

Figure 2 is an end elevation of the same.

Figure 3 is a perspective view showing the 30 inner side of one of the plates.

Figure 4 is a sectional view on the line 4—4 of Figure 3.

Figure 5 is a side elevation of the plate shown in Figure 3.

35 Figure 6 is a view in elevation of a modification of the form of structure shown in Figures 1 and 2.

Figure 7 is an end elevation of the same.

Figure 8 is a side elevation of still another form 40 of construction.

Figure 9 is an end elevation thereof.

Figure 10 is a side elevation of still another embodiment of the invention.

Figure 11 is an end elevation of the structure 45 shown in Figure 10.

Figure 12 is a side elevation of another embodiment of the invention.

Figure 13 is an end elevation thereof.

Figure 14 is a detail perspective view of one 50 of the plates shown in Figure 14.

Figure 15 is a similar view of two of the plates in assembled relation and indicating how the said two plates may be formed of sections in parallelogram.

55 Referring first to the embodiment disclosed in

Figures 1 and 2, a portion of a tubular tunnel lining is shown and consists of rows of plates 20, the plates of each row being located to form a ring, and the rows being disposed side by side. As these plates are duplicates, the detail showing 60 of one in Figures 3, 4 and 5 and a description thereof will suffice for all. The plate is preferably formed of plate metal, comprising an outer curved body wall 21, which may be reinforced or stiffened by circumferential ribs 22. Along 65 each of the side edges of the body plate are inset flanges 23 and 24 that are perforated as illustrated at 25 to receive fastening bolts, rivets or the like. It will be noted that the body wall 21 is in the form of a parallelogram so that the 70 flanges 24 and the edges carrying the same, are disposed diagonally to the other flanges 23.

When these plates are assembled to produce the lining structure or as shown in Figures 1 and 2, the flanges 23 of adjacent plates are located 75 side by side and are suitably secured together in a well-known manner. The flanges 24, are however disposed diagonally to a plane perpendicular to the axis of the tunnel, the diagonal flanges of one plate abutting and being secured to the diagonal flanges of adjoining plates in the same row. More than that, it will be noted that these diagonal lines or joints of one row are staggered with relation to those of the adjacent rows, so that the diagonal flanges 24 will abut against 85 the flanges 23 of the plates of the adjacent row between the ends of said latter flanges.

As a consequence a structure is formed, each ring of which may be considered as a continuous truss (Figure 1), which when placed under 90 stress by an external load, will tend to distort by rotating one chord in one direction and the other chord in the opposite direction, a tendency that is resisted by the webs or bodies of the plates.

In Figure 6 the plates are designated 20a, and 95 their structure is the same as that disclosed in Figures 3, 4 and 5, saving that the form of the parallelogram of the body wall is reversed so that the straight lines of joints run longitudinally of the tunnel rather than circumferentially of the 100 same. It will be obvious however, that the action is precisely the same as that heretofore described, except that the chords of the trusses are longitudinal instead of circumferential.

In the structure disclosed in Figures 8 and 9 105 the plates are designated 20b and it will be noted that the parallelogram formation of the body wall of each is the same as heretofore described. In other words their general structure including the flanges is the same as in Figures 3, 4 and 5. 110

In this form of structure, however, the plates of adjacent rows are reversed. That is to say, the joints of one row extend diagonally in one direction and the joints of the adjacent row extend diagonally in an opposite direction. The same effective results are, however, obtained.

The structure illustrated in Figures 10 and 11 is very similar to that illustrated in Figure 8, except that the continuous straight line joints 10 are extended longitudinally of the tunnel instead of circumferentially thereof. The plates are here designated 20c and it will be noted that the rows extend longitudinally of the tunnel to produce said longitudinal joints. The plates of 15 one row, however, have their diagonal joints and edges extended in an opposite direction from the diagonal edges and joints of the plates of the adjacent row. They still, however, are staggered as in the disclosure illustrated in Figure 8.

20 Figures 12 and 13 disclose a structure in which the rows run longitudinally of the tunnel instead of circumferentially, forming a series of trusses. Triangular plates 20e are provided, with alternate plates of each row reversely arranged and 25 with the apex of the plate of one row abutting the base of the plate of the next row. As will be clearly evidenced by a comparison of Figures 12, 13 and 15 two of these plates may be considered as the sections of a parallelogram and in this respect are very similar to the disclosure shown in 30 the first forms of the invention.

From the foregoing, it is thought that the construction, operation and many advantages of the herein described invention will be apparent to 35 those skilled in the art without further description, and it will be understood that various changes in the size, shape, proportion and minor details of construction may be resorted to without departing from the spirit of sacrificing any 40 of the advantages of the invention.

What we claim, is:

1. A tubular structure comprising separate rows of plates, the rows being located side by side, each of said plates being a substantial parallelogram having parallel sides forming the sides of the rows, and parallel ends disposed diagonally of the sides, the correspondingly disposed diagonal ends of abutting plates in a row extending diagonally across the row.
- 45 2. A tubular structure comprising separate rows of plates, the rows being located side by side, each of said plates being a substantial par-

allelogram having parallel sides forming the sides of the rows, and parallel ends disposed diagonally of the sides, the correspondingly disposed diagonal ends of abutting plates in a row extending diagonally across the row and out of line with the joints between the abutting ends of the plates of adjacent rows.

3. A tubular structure comprising separate rows of plates, the rows being located side by side, each of said plates being a substantial parallelogram having parallel sides forming the sides of the rows and parallel ends disposed diagonally of the sides, the joints between the ends of the plates in each row extending in the same direction and in opposite directions to the joints of the plates of adjacent rows.

4. A tubular structure comprising separate rows of plates, the rows being located side by side, each of said plates being a substantial parallelogram having parallel sides forming the sides of the rows and parallel ends disposed diagonally of the sides, the correspondingly disposed diagonal ends of abutting plates in a row extending diagonally across the row, said rows forming continuous rings side by side with the sides of the rings and of the plates being disposed in planes perpendicular to the axis of the tubular structure.

5. A tubular structure comprising separate rows of plates, the rows being located side by side, each of said plates being a substantial parallelogram having parallel sides forming the sides of the rows and parallel ends disposed diagonally of the sides, the correspondingly disposed diagonal ends of abutting plates in a row extending diagonally across the row, said rows extending longitudinally of the axis of the structure and the diagonal ends of the different rows being alternated and producing broken joints extending around the structure.

6. A tubular structure comprising rows of plates extending longitudinally of said structure and said rows having substantially parallel sides extending in said longitudinal directions, the sides of the plates of one row being secured to the sides of the plates of adjacent rows and forming joints between the rows that are extending longitudinally of the structure, the ends of the plates of each row being secured together and forming joints across said longitudinal rows.

JULIUS KAHN.
HERBERT E. WHITE.
